UNITED STATES PATENT OFFICE.

HOLCOMBE J. BROWN, OF CHICAGO, ILLINOIS.

CENTRIFUGAL HAIR-SEPARATOR.

No. 838,377.

Specification of Letters Patent.

Patented Dec. 11, 1906.

Application filed May 2, 1904. Serial No. 206,005.

To all whom it may concern:

Be it known that I, HOLCOMBE J. BROWN, a citizen of the United States, residing at Chicago, in the county of Cook and State of Illinois, have invented certain new and useful Improvements in Centrifugal Hair-Separators, of which the following is a specification.

The invention relates to that class of machines which are designed for the purpose of economically and perfectly fiberizing, picking, separating, and cleaning all kinds of hair, fibers, &c., as will more fully hereinafter appear.

The principal object of the invention is to provide a simple, economical, and efficient machine for separating, picking, and cleaning all kinds of hair and fibrous materials.

Other and further objects of the invention will appear from an examination of the drawings and the following description and claims.

The invention consists principally in an organized machine in which there are combined a supporting-frame, a rotatable member therein provided with teeth or similar elements projecting longitudinally therefrom, and a stationary member arranged adjacent thereto and provided with teeth projecting longitudinally therefrom and intermeshing with the teeth on the rotatable member, whereby during the rotation of the parts centrifugal force is developed and the material to be operated upon fed forward thereby to be subjected to the picking action of the teeth.

The invention consists, further and finally, in the features, combinations, and details of construction hereinafter described and claimed.

In the accompanying drawings, Figure 1 is a side elevation of one type of machine as it appears when constructed in accordance with these improvements; Fig. 2, a front elevation of the inclosing casing, with part of the forward wall or stationary plate broken away; and Fig. 3, a sectional plan view of a portion of the mechanism, taken on line 3 of Fig. 1 looking in the direction of the arrow.

In constructing a machine in accordance with these improvements I make a supporting-frame *a* of the desired size, shape, and strength to support and hold the operative and other parts in position for use. This supporting-frame portion is provided with two bearing-boxes *b*, made in two parts—a lower part integral with the supporting-

frame and an upper part in the shape of caps *c*, held in position by means of the bolts and nuts *d*. These boxes are babbited, as at *e*, in the usual manner.

To perform the functions of the machine—that is, the cleaning, fiberizing, and separating of the materials—a rotatable shaft *f* is provided and rotatably journaled in the bearing-boxes *b*, above referred to. The front end of this shaft is provided with a disk *g*, rigidly attached thereto, formed either, as shown in the drawings, integral therewith or to be made in a separate plate and otherwise secured in any ordinary manner to the rotatable shaft and in such way as to be rotated thereby. This rotatable disk is the principal feature of the machine in that it is provided with the fiberizing elements and during its rotation develops sufficient centrifugal force, as will be hereinafter more fully shown, to force the material through the machine, and thereby subject it to the picking elements. In order to provide for these results, the rotatable disk is provided with a plurality of picking-teeth *h*, formed of shouldered pins longitudinally arranged (see Fig. 3) and passed through perforations in the plate and headed on their inner ends. It will be understood, of course, that these picking-teeth may be formed in a variety of shapes and attached to the plate in any one of a number of equally-efficient methods. As shown in Fig. 2, these picking-teeth are arranged in radial and circular lines and project forward from the front face of the rotatable disk, which is also provided with a number of serrations or ratchet-shaped teeth *i* on its peripheral surface. These ratchet-shaped teeth grasp the material, carry it around with them, and discharge it when opposite the outlet or discharge opening, as will be more fully herein-after set forth.

To form the second element of the fiberizing mechanisms, a stationary plate *j* is used and arranged parallel with and in front of the rotatable plate. This stationary plate is provided with a multiplicity of inwardly-projecting longitudinally-arranged picking-teeth *k*, also arranged in radial and circular lines, as shown in Fig. 2, so as to intermesh with the forwardly-projecting teeth on the rotatable plate, as shown in Fig. 3. This arrangement is such that the material is brought into successive contact with the picking teeth or pins when it is fed in and

subjected to centrifugal action and separated or fiberized and cleaned, all of which will more fully hereinafter appear.

To complete the mechanism, an inclosing 5 casing is provided, preferably formed of a rear wall *l*, secured to the supporting-frame of the machine by means of brackets *m*, a peripheral wooden ring *n*, and the forward stationary plate *j*, above described, all arranged 10 so as to substantially entirely surround the rotatable disk, thus confining the material and assisting in guiding it through the machine during the operations thereof, except as hereinafter set forth.

15 The stationary disk is further provided with a centrally-arranged inlet-opening *p*, and the peripheral ring *n* is broken away, as shown in Fig. 2, for about one-eighth of its circumference, so as to form a discharge-opening *q*. Attached to the supporting-plate opposite the inlet-opening is a feeding-hopper *r* of such construction that the material may be dumped therein and fed into the machine. The different parts of the inclosing 20 casing are secured together by means of a plurality of securing bolts and nuts *t*, (shown particularly in Figs. 2 and 3,) all of which permits the parts to be readily associated and disassociated whenever desirable or 25 necessary.

In operation the material to be treated is admitted through the inlet-opening, where it is caught by the teeth on the rotatable disk and carried around, in the process of 30 which the teeth on the stationary plate retard the progress, resulting either in the clean separation of the hair from a clotty mass or the fiberizing of other materials. This operation is repeated in a step-by-step 35 manner as the materials are forced out with the aid or during the action of the centrifugal force developed during the rotation of the disk until it reaches the space *u*, formed between the toothed periphery of the rotatable 40 disk and its outer inclosing wall. Here the separated material is carried around by the teeth on the disk until it comes opposite the discharge-opening, from whence it is discharged.

45 In addition to the centrifugal force developed, which aids in the passage of the material through the machine, as above described, a strong current of air is set in motion by the air entering the inlet-opening and exhausting through the discharge-opening, which current of air assists in cleaning the fiber of all 50 dirt. The different materials—such as dust,

dirt, and fiber—take various trajectories as they are ejected through the discharge-opening, owing to their difference in weight or 60 specific gravity, thus acting to effectually clean the hair or fiber acted upon, all of which will be understood and appreciated by those skilled in the art.

I claim—

1. In a machine of the class described, the combination of a supporting-frame portion, a disk rotatably mounted therein, teeth projecting from the face thereof, teeth upon the periphery thereof, a supporting member 70 upon which such disk is mounted, a stationary plate mounted beyond the end of such disk, and carrying teeth extending between the teeth upon the face of the rotatable disk, substantially as described.

2. In a machine of the class described, the combination of a circular inclosing chamber having a peripheral opening therein, a disk rotatably mounted in such chamber, projecting teeth upon one side of such disk, teeth upon 80 the outer periphery of the disk, a stationary disk, teeth thereon projecting between the teeth upon the face of the rotating disk, a hopper for feeding material to the inner part 85 of the disk, and means for separating such material and discharging the same through the opening in the periphery of the inclosing chamber, substantially as described.

3. In a machine of the class described, the combination of a supporting-frame, a shaft 90 rotatably mounted therein, a disk secured to such shaft so as to be rotated thereby, a multiplicity of picking teeth or pins rigidly secured to the forward face of the said rotatable disk and extending longitudinally 95 therefrom, a plurality of teeth on the periphery of said disk, a stationary disk arranged parallel with and in front of the rotatable disk, a plurality of teeth rigidly secured to the inner face of such stationary disk and 100 projecting inwardly and longitudinally therefrom so as to intermesh with the teeth on the rotatable disk, a casing inclosing said rotatable disk the front wall of which is formed by said stationary disk and provided with 105 an inlet-opening substantially centrally arranged and a peripheral outlet-opening, and a feeding-hopper secured to the inclosing casing at the central inlet-opening, substantially as described.

HOLCOMBE J. BROWN.
